UNDERFEED STOKER GRATE

Forrest L. Hitchcock, Indianapolis, Ind., assignor
to FurnasSlave, Inc.

Application May 14, 1934, Serial No. 725,557

8 Claims. (Cl. 110—45)

This invention relates to the art of stokers and particularly to a grate bar structure to be used in an under-feeding stoker. An important object of the invention is to provide a grate structure which will not only aid in preventing the coking over of fuels thereon but will also cause ashes to sift down therethrough and to grind clinkers into small particles which will pass between the bars of the grate.

An important object of the invention is to provide a grate structure wherein individual bars will have a longitudinal shearing action one past the other so as to effect a crushing or grinding action on particles becoming engaged therebetween.

Another important object of the invention is to provide a grate structure which will receive fuel centrally therethrough and cause the fuel to spread outwardly to promote a fire bed extending to the outermost part of the grate structure. A still further important object of the invention is to so shape the grate bars that upon being shifted, the ashes and clinkers resulting from the combustion of the fuel will be worked outwardly from the center thereof so as to bring the larger particles in particular in the ashes to those zones over the bars wherein the maximum shearing action therebetween takes place.

These and other objects and advantages will become apparent to those skilled in the art in the following description of one particular form of the invention as illustrated by the accompanying drawings, in which

Fig. 1 is a fragmentary top plan view of a structure embodying my invention;

Fig. 2, a fragmentary central longitudinal vertical section through the structure;

Fig. 3, a detail in top plan view of a pair of grate bars in shifted positions;

Fig. 4, a section on the line 4—4 in Fig. 3;

Fig. 5, a top plan view of an elongated grate structure;

Fig. 6, a detail in vertical section on the line 6—6 in Fig. 5;

Fig. 7, a detail in top plan view of the filler ring; and

Fig. 8, a detail in section on the line 8—8 in Fig. 7.

Like characters of reference indicate like parts throughout the several views in the drawings.

I employ a fuel conducting tube or pipe 10 which is supported by its inner end within a furnace to which the device is to be applied by a foot 11 which carries an adjustable leg 12 to extend downwardly and bear on the floor. The inner end of the pipe 10 turns upwardly to carry a sleeve 13 in fixed relation thereto. This sleeve has an internal diameter corresponding to that of the upturned end of the pipe 10 so as to in effect form a continuation thereof. Toward the

upper end of the sleeve 13 is provided a flange 14 extending horizontally therefrom. This flange 14 is provided with a plurality of openings 15 to permit the passage of air upwardly therethrough externally of the sleeve 13. The outer edge of the flange 14 is formed to have a step 5 extending therearound on which is revolubly received a plate 16, the plate being mounted thereby centrally of the sleeve 13. Preferably the plate 16 is provided with a cylindrical depending skirt 17 from which braces 18 extend upwardly and outwardly to the under side of the plate 16 as a means of reenforcing it to prevent warping. This skirt 17 is open from the under side so that air may pass up therethrough to discharge 10 through the holes 15.

The plate 16 is provided with a plurality of openings 19 therethrough so as to provide for the passage of air through the plate externally of the skirt 17. On the top side of the plate 16 are carried a plurality of pins 20 equally spaced apart around a common circumference near the periphery of the plate. A collar 21 engages over the upper end of the sleeve 13 to rest on the flange 14 and extend upwardly therefrom. This collar 21 has an outwardly extending annular flange 22 20 at its upper end, in which flange are provided a plurality of holes 23. The number of holes 23 correspond to the number of pins 20.

I provide a plurality of individual grate bars 24, two only being shown in Fig. 1 for the sake of clearness. Each of these bars 24 has a more or less triangular shape in top plan view with a substantially arcuate vertical cross section. The inner end of the bar is provided with a pin 25 30 extending vertically downwardly therefrom to pass through a hole 23 in the flange 22 and preferably a foot or lug 26 extends from one side of the pin 25 horizontally to engage against the under side of the flange 22 toward the sleeve 21 35 whereby the inner end of the bar may not be lifted vertically but may be only disengaged from the flange 22 by raising the outer end of the bar so as to rock the lug 26 around to permit its withdrawal through the hole 23 in the flange. It is to be understood that there is sufficient freedom of the pin 25 in the hole 23 to permit this rocking movement. The outer end of the bar 24 curves around downwardly to bear on the top side of the plate 16 which in the one form here shown 40 is in a plane below that of the top face of the flange 22. The outer end of the bar 24 is radially notched to provide a slot 27 into which extends a pin 20. By means of the pin 20 extending into this slot 27 the bar 24 is thus normally held 45 against rotation of the pin 25 in the flange 22.

The lateral edges of each bar are in effect serrated with the tooth-like projections blunt on their outer edges and each terminating in the plane of the side of the bar. Preferably the bar 50

is provided with some of the teeth having higher elevations than the major surface of the bar, such as the teeth 28, Fig. 2. In turn these teeth have their inner ends united by a rib 29 in each case extending down around the upper surface of the bar.

The skirt 17 is provided with a pair of diametrically opposed legs 30 having respectively the out-turned feet 31 and 32, Fig. 1. Connecting rods or bars 33 and 34 respectively pivotally attached by their ends to these feet and carried outwardly along the pipe 10 to have their other ends pivotally interengaged with a yoke bar 35 which is rockably attached to the upper side of the pipe 10. The pivot point of the bar 35 is at its center so that when the bar 35 may be rocked about that central pivot point which is here shown as being formed by the cap screw 36, the rods 33 and 34 are given a reciprocatory motion as indicated by the dash lines, Fig. 1, to in turn cause a corresponding reciprocation of the plate 16 around the flange 14.

Now since the collar 21 is held in a stationary position by the sleeve 13 which is also held stationary, the inner ends of the respective grate bars 24 are not shifted circumferentially although the outer ends thereof do shift circumferentially as indicated by the dash lines, Fig. 1, where the dash lines indicate the bars as having been shifted to substantially their limit of travel in a counter-clockwise direction. This position is better shown in the detail, Fig. 3, where it is to be noted that there has been a longitudinal movement between opposing faces of adjacent bars 24 so that, for example, a tooth 37 which in the solid line position, Fig. 1, matched up with the opposing tooth 38 on the adjacent bar has been shifted to be opposite the next inner notch at the side of the tooth 38. Of course when the yoke 35 is shifted in the opposite direction, the bars are likewise moved by their outer ends circumferentially as the pins 20 carry the outer ends of the bars therealong the reversed movement of opposing faces of adjacent bars is obtained whereby the tooth 37 will thereby be relatively shifted to be on the outer side of the tooth 38.

Thus it is to be observed that in the relative longitudinal movement of one bar past another, particles of ashes will be worked down through the notches between the teeth and also, clinkers extending between the teeth will be engaged by teeth of the adjacent bar and ground off as the teeth of one bar move past the teeth of the adjacent bar. The occasional upwardly extending teeth 28 aid in causing a better grip to be obtained upon clinkers so as to facilitate the grinding action. The yoke 35 is reciprocated through some suitable mechanism driven by the fuel feed driving motor 39 which through a suitable transmission mechanism causes a relatively slow rotation of a ratchet wheel 40, Fig. 1, from which extends a pin 41 to engage a connecting rod 42 by one end thereof. This rod 42 has its other end pivotally attached to the yoke 35 whereby the yoke 35 may be reciprocated by the rotation of the wheel 40. Rotation of the wheel 40 is effected by means of the pawl 43 carried by a rocker arm 44 which is in turn slotted to receive a roller 45 within the slot. This roller 45 is mounted on the wheel 46 which in turn is driven through a reduction gearing by the motor 39. The particular driving mechanism just described is only indicated as being one possible driving means for reciprocating the yoke 35 and

the specific form does not enter into my present invention herein described.

In operation, fuel feeds down through some suitable means such as a chute 47, Fig. 1, to drop into the feed conductor 10 through which it is caused to travel by some suitable means such as by a ram 48 driven by the motor 39. The fuel is fed through the pipe 10 and discharged upwardly through the sleeve 13 to have the fuel discharge outwardly on to the upper sides of the bars 24. As the bars 24 are given the reciprocatory motion at their outer ends, the fuel will gradually work radially outwardly toward the wall 49 of the combustion chamber. The particular curvature of the bars 24 may be varied in accordance with the fuel to be burned but in any event, the downward curvature at the outer end of each bar is provided so that the ashes and clinkers will be worked radially outwardly and downwardly toward the wall 49. Air for combustion purposes may travel upwardly through the holes 15 and 19 as above indicated. Also the holes 19 provide surfaces through which the ashes may drop as they fall through between the grate bars.

Referring to Figs. 5 and 6, the same mode of operation may be incorporated in an elongated grate structure so as to obtain the same longitudinal shearing action between adjacent grate bar edges. Referring to the modified form, the circular plate 16 is here shown as being separated into two spaced apart halves 51 and 52 each rockably carried about rounded ends 53 and 54 respectively of a fuel feeding throat 55. These halves 51 and 52 are tied together by the inner links 56 and 57 so as to retain the halves in slideable, rockable contact with the supporting ends 53 and 54. The links 56 and 57 are pivotally interengaged by their ends so as to permit the rocking action. Furthermore the outer ends of the halves 51 and 52 are tied together by the links 58 and 59 also pivotally connected therewith. The same grate bars 24 are employed around the circular halves 51 and 52 as in the form above described. Between the circular sections are interposed a sufficient number of parallel side bars 60 to fill in the spaces therebetween with sufficient freedom to permit the outer ends of these bars 60 to be horizontally reciprocated by pins 61 carried by the links 58 and 59 to enter within the slots provided in the outer ends of the bars. It is to be understood that the inner ends of the bar 60 are pivotally connected with the links 56 and 57 by the down-turned pins 62 of the same structure as the pins 25 and lugs 26 so that the inner ends of these bars are not laterally displaced but are pivotally maintained so that when the outer ends are reciprocated, the same shearing action is set up between the longitudinal adjacent edges of the bars as is produced between the radially disposed bars 24.

Reference is made to my copending application for U. S. Letters Patent for Fuel supply and control system filed May 14, 1932, Serial No. 611,285 of which this is a continuation in part.

Referring to Figs. 2, 7, and 8, I provide means for preventing air from passing up around the outer ends of the grate bars adjacent the refractory lining of the fire bowl in the form of a sectional filler ring generally designated by the numeral 65. This ring is circumferentially expandable so that it may be brought into circumferential contact with the bowl. Each section 66 has an end resting on a depressed end of the adjacent depressed end of the adjacent section 67 to

be joined thereto by a countersunk headed screw 68 extending through a tapered slot 69 to screw-threadedly engage the depressed end. The ring 65 is supported by arms 70 carried by a collar 71 mounted on the upturned end of the fuel pipe 10. There is an arm 70 for each section of the ring which is fixed to the arm by a countersunk headed screw 12 passing through a tapered radial slot 73 in the section to screw-threadedly engage the 10 arm underneath.

The plate 16 does not bear on this filler ring 65, but is spaced thereabove slightly so that ash may sift thereunder to fill in on the ring 65 so as to form an air seal to cause the air to pass through 15 between the grate bars removed from the outer ends to where the clinkers are carried.

While I have herein shown and described my invention in more or less minute detail in the form as now best known to me, it is obvious that 20 structural changes may be made without departing from the spirit of the invention and I, therefore, do not desire to be limited to that particular form any more than may be required by the following claims.

25 I claim:

1. A burner for an underfeed stoker, comprising in combination with a furnace fire bowl and a fuel supply pipe directed to discharge fuel upwardly centrally of the bowl; an annular plate 30 slidably supported by said pipe for horizontal oscillation thereof, the outer portion of the plate being within and adjacent the inner wall of the fire bowl; a collar supported in fixed position about said pipe; a plurality of radially disposed 35 grate bars resting by their inner ends on said collar and by their outer ends on said plate outer portion; means pivotally interconnecting the inner ends of the bars to said collar, said means being formed to provide for horizontal oscillation of the bars about the pivot connections but preventing rotation of the bars about their axes; pins on said plate slidably engaging the outer ends of said bars to fix the circumferential locations of the bars with respect to said plate; each 40 of said bars being formed with an upper curved face sloping from the pipe upwardly and outwardly and thence downwardly to provide in effect a flared end for said pipe; means preventing the lifting of the inner ends of said bars as fuel 45 passes from said pipe over the inner ends of said bars; and means for oscillating said plate, whereby the outer end of each of said bars is horizontally shifted about its inner end as a center and the longitudinal alignment of adjacent bars is 50 varied.

55 2. A burner for an underfeed stoker as defined in claim 1 including an adjustable filler ring, and means supported by said pipe for positioning said ring against the inner wall of said bowl and beneath the outer portion of said plate.

3. A burner for an underfeed stoker as defined in claim 1 characterized by said pipe having an outwardly extending, circumferential flange, and said plate being slidably carried by said flange.

60 4. A burner for an underfeed stoker as defined in claim 1 characterized by said pipe having an outwardly extending circumferential flange, and said plate being slidably carried by said flange, a skirt extending downwardly from said plate adjacent said flange and encircling said fuel pipe in spaced relation; said flange having openings therethrough to permit air to travel up within 65 the skirt and discharge through the openings; 70

said skirt being fixed to said plate; and a pair of arms pivotally connected one each to a diametrically opposite side of the skirt; said reciprocating means being connected to said arms to provide for oscillation of said plate. 5

5. A burner for an underfeed stoker as defined in claim 1 characterized by said pipe having an outwardly extending circumferential flange, and said plate being slidably carried by said flange; and a skirt extending downwardly from said plate adjacent said flange and encircling said fuel pipe in spaced relation; said flange having openings therethrough to permit air to travel up within the skirt and discharge through the openings, whereby an upwardly directed current of air 15 is maintained about said sleeve.

6. A burner for an underfeed stoker as defined in claim 1 characterized by said pipe having an outwardly extending circumferential flange, and said plate being slidably carried by said flange; 20 and a skirt extending downwardly from said plate adjacent said flange and encircling said fuel pipe in spaced relation; said flange having openings therethrough to permit air to travel up within the skirt and discharge through the opening 25 whereby an upwardly directed current of air is maintained about said sleeve; said collar forming the upper end of said pipe and being above said flange.

7. For an underfeed stoker burner, a grate- 30 bar having an upper centrally closed face generally triangular in shape; a pivot pin extending downwardly under the apex end; and a lip outwardly turned from the outer side of the pin; said bar being formed to have said face slope upwardly 35 from both apex and base ends to a central portion having a higher elevation than either end forming in effect a centrally humped bar, said bar being notched along its sides to leave laterally extending teeth terminating in the side lines of 40 said face; and some of said teeth along the portion of the bar which curves downwardly toward the bar base having their upper faces above the elevation of the adjacent bar face, the other of 45 said teeth having their upper faces remaining at 50 the respective face elevations.

8. A burner for an underfeed stoker, comprising in combination with a furnace fire bowl and a fuel supply pipe directed to discharge fuel upwardly centrally of the bowl; a plurality of grate 50 bars carried within the bowl radiating from around said pipe toward the inner wall of said bowl, said bars each being formed to slope upwardly from said pipe and then outwardly and finally abruptly downwardly over their outer ends 55 to define an annular V-shaped pocket between the outer end portions of the bars and said wall, the angle between the bars and wall being not more than 45 degrees, means for horizontally 60 oscillating the outer ends of said bars, means pivotally retaining the inner ends of the bars, and laterally extending teeth along adjacent edges of said bars; whereby a column of fuel discharging upwardly from said pipe may expand outwardly against the inner end portions of said bars as the 65 fuel travels upwardly, the inner end portions of the bars having less travel than the outer end portions, and ashes and clinkers resulting from combustion of said fuel will be worked outwardly into said pocket to be crushed between said downward end portions of said bars and said wall and between adjacent teeth by the relative longitudinal displacement of adjacent bars. 70

FORREST L. HITCHCOCK.
